UNITED STATES PATENT OFFICE.

REUBEN C. BAKER, OF COALINGA, CALIFORNIA, ASSIGNOR TO BAKER CASING SHOE CO.,
A CORPORATION OF CALIFORNIA.

WELL-CASING SHOE.

1,078,530.

Specification of Letters Patent. Patented Nov. 11, 1913.

Application filed November 4, 1912. Serial No. 729,185.

To all whom it may concern:

Be it known that I, REUBEN C. BAKER, a citizen of the United States, residing at Coalinga, in the county of Fresno and State 5 of California, have invented a new and useful Well-Casing Shoe, of which the following is a specification.

The device herein disclosed is adapted to be employed for drilling Artesian and oil 10 wells and particularly to be employed for reaming out a small bore, so that the same may receive the well tubing.

The invention aims to provide a cutter which will not clog, the material detached 15 by cutting elements being permitted to drop between the openings existing between the cutting elements of a lower set.

A further object of the invention is to provide a tool of the class mentioned, in 20 which the entire cutting strain will not be carried by a single series of cutters.

With the foregoing and other objects in view which will appear as the description proceeds, the invention resides in the combination and arrangement of parts and in the details of construction hereinafter described and claimed, it being understood 25 that changes in the precise embodiment of invention can be made within the scope of what is claimed without departing from the spirit of the invention.

In the drawing:—Figure 1 shows the invention in side elevation; Fig. 2 is a longitudinal section; and Fig. 3 is a bottom plan.

The cutter herein disclosed comprises a cylindrical shell 1 adapted to be connected with a driving member in any suitable manner. In the present instance, the shell is internally threaded, intermediate its ends 35 as indicated at 3, the wall of the shell 1 being thickened adjacent the lower end of the shell, as shown at 4, to define a shoulder 5 at the lower end of the threaded portion 3, the shoulder 5 constituting an abutment 40 for the driving member. Adjacent its lower end and upon its outer surface, the shell 1 is flared slightly as shown at 2, to provide the necessary clearance.

Formed upon the lower end of the shell 1 are a plurality of cutters 6. Above the cutters 6 are located other cutters 7, and above the cutters 7 are located other cutters 8. The several cutters are disposed in circles. The diameter of the circle in which the cutters 7 are disposed, is greater than the 50 diameter of the circle in which the cutters 6 are disposed, and less than the diameter of the circle in which the cutters 8 are disposed. The cutters 7 lie above the openings 9 between the cutters 6. The cutters 7, 60 however, overhang the cutters 6, partially, circumferentially of the shell 1. The cutters 8, however, are located directly above the openings 10 which exist between the cutters 7. 65

The construction is such that the material removed by the cutters 7 will drop downwardly into the openings 9 between the cutters 6, the material removed by the cutters 8 passing downwardly through the openings 10 which exist between the cutters 7. 70 Owing to this fact, and to the further fact that the several sets of cutters are disposed in circles, the diameters of which increase toward the upper end of the tool, the tool 75 will clear itself readily, in operation, and will not clog. Further, it is to be noted, the entire boring operation is not confined to any one set of cutters, the boring strain being distributed between the several sets 80 of cutters, and the effective life of the tool being increased accordingly.

It will be understood readily that there may be any number of cutters to any one set, the cutters being formed in any desired shape and size, and the spaces between the cutters being positioned as may be desired.

Having thus described the invention what is claimed is:—

1. A well boring tool provided at its lower end with superposed sets of spaced cutters, the cutters of each upper set being located above the openings between the cutters of the next lower set.

2. A well boring tool provided at its lower

2
end with superposed sets of spaced cutters, the cutters of each upper set being located above the openings between the cutters of the next lower set, the cutters of each set being disposed in a circle, the diameters of the circles increasing in the direction of the top of the tool.

In testimony that I claim the foregoing as my own, I have hereto affixed my signature in the presence of two witnesses.

REUBEN C. BAKER.
